CLAIM

The ornamental design for an appliance with a front having the appearance of chamfered sides with rounded edges, as shown and described.

DESCRIPTION

FIG. 1 is a front perspective view of the first embodiment of an appliance with a front having the appearance of chamfered sides with rounded edges illustrated in the environment of a microwave with a door and control panel each having an outer side having the appearance of a chamfered side and a top trim panel with the appearance of chamfered sides with rounded edges.

FIG. 2 is a top view of the first embodiment of the appliance of FIG. 1.

FIG. 3 is a front perspective view of the second embodiment of an appliance with a front having the appearance of chamfered sides with rounded edges illustrated in the environment of a microwave with a door and control panel each having an outer side having the appearance of a chamfered side and a top trim panel with the appearance of chamfered sides with rounded edges; and,

FIG. 4 is a top view of the second embodiment of the appliance of FIG. 3.

The structures depicted by means of broken lines in the figures have been shown for illustrative purposes only and form no part of the claimed design.
